UNITED STATES PATENT OFFICE

WALTER OPAVSKY, OF SIEGEN, GERMANY

APPARATUS FOR DRYING GOODS OF ANY CHARACTER

Application filed March 21, 1928, Serial No. 263,570, and in Germany September 21, 1927.

My invention relates to improvements in the method of and apparatus for drying things of any kind, for example a method of and apparatus for drying objects having a 5 coating of lacquer. I wish it to be understood that my improved method may be used for drying goods of any other character, for example wood, ceramic objects, wool, dough, vegetables, fruit and the like. For drying 10 objects of this nature a system is used which consists of a case adapted to receive the articles to be dried, a fan or blower connected at its suction and pressure sides with the said case and adapted to circulate a current of air 15 through the said case, and means for heating the said current of air. In the practical operation the efficiency of the apparatus has been found to be unsatisfactory for the reason that the current of air is more and more saturated with moisture, so that vaporization is 20 gradually reduced. Further, the drying of articles having a coating of lacquer is unsatisfactory, because the said coating of lacquer is not sufficiently exposed to the action of 25 oxygen.

The object of the improvements in this case is to provide a method of and an apparatus for drying articles of the character referred to, which method is more satisfactory in operation. More particularly my improved method is adapted for drying objects having a coating of lacquer, and I have found that by my improved method the time required for drying the coating of lacquer is reduced, and 35 the result obtained is improved in so far as a better and more elastic coating of lacquer is obtained. With these objects in view my invention consists in continuously removing a part of the air or gas circulated through the 40 case, and more particularly a part of the said air or gas which is particularly loaded with vaporized moisture, vapor or the like, the said portion of the air being replaced by fresh air or gas supplied to the current of air 45 flowing into the case. Thus the current of air maintains the greater part of its heat, and further, it is regenerated in its oxygen contents and in its vaporizing property.

In carrying out the invention I make use 50 of an apparatus for separating a part of the

moisture or vapor from the current of air, the said moisture or vapor being separated by centrifugal action, so that a comparatively high percentage of the moisture or solvent is removed with the air. For taking fresh 55 air or fresh gas into the circulating current an injector or ejector may be provided, or the said air or gas is forced into the case or into the conduit connecting the same with the fan or blower by means of a pump. 60

In a modification of the method I supply ozoniferous air to the current of air for removing the bad odour of the vapor escaping from the case or through the doors thereof, which vapors are obnoxious to the attendants. 65 Further, by the said ozoniferous air the drying operation is improved. Preferably means are provided for continuously generating ozone in the supply of fresh air used for replacing the mixture of air and vapor removed from the circuit. Any known or preferred apparatus for generating ozone may be provided, for example I make use of an apparatus operated by electric energy of high 70 voltage. 75

For the purpose of explaining the invention two examples embodying the same have been shown in the accompanying drawing, in which

Fig. 1, is an elevation partly in section showing the apparatus, and

Fig. 2, is an elevation showing a modification.

In the example shown in Fig. 1 the drying system comprises a case *a* provided internally with shelves adapted to have the articles to be dried placed thereon, a fan *c* having its suction pipe connected with the case, a separating receptacle *d* connected with the fan *c* by a pipe *b* and communicating with the bottom part of the case *a* through a pipe *b*', and heating means *f* disposed in the bottom part *e* of the case *a*, the said heating means being for example in the form of an electrically heated coil. The bottom part *e* is connected with a supply *g* for fresh air. The pipe *b* opens into the receptacle *d* in tangential direction, so that the current of air is delivered from the fan *c* into the separator *d* at the side thereof so as to move through the same along 100

a helical path. Therefore the heavier particles such for example as benzol are thrown outwardly by centrifugal action and collected at the bottom of the separator *d*, from whence they are discharged together with a part of the air through a pipe *i*. The air from which the benzol has been separated is passed through the intake *k* of the pipe *b*¹ and into the bottom part *e* of the case *a*. Before traversing the heating system *f* the said current of air takes in by suction a certain amount of fresh air admitted through the pipe *g*. Together with the vaporized solvent other foreign matter and more particularly particles of dust are separated from the current, so that air which is free of dust and which contains much oxygen is passed in contact with the goods having a coating of lacquer and contained within the case *a*. Therefore the goods are rapidly dried and a coating of superior quality is obtained.

The apparatus illustrated in Fig. 2 is similar to the one shown in Fig. 1. But in addition an apparatus for producing ozone is connected to the system. As shown, the said apparatus *m* is connected by a pipe *g*¹ with the intake pipe of the fan or blower *c*. The apparatus *m* may have any known construction, and it has a supply of fresh air, the said air being ozonized. The supply of fresh air through the bottom of the case is dispensed with, and all the air discharged through the outlet *i* is replaced by air flowing through the ozonizing apparatus *m*.

35 I claim:

A drying apparatus for lacquered articles and the like, comprising a main case providing an air drying chamber for the articles, a secondary case forming a cleaning chamber 40 for the drying air, a conduit leading from the upper end of the drying chamber to the upper end of the cleaning chamber and opening thereinto at a tangent for circulating the air downwardly in a spiral path within the 45 cleaning chamber and depositing the heavy matter within the secondary case, means for removing the heavy matter from the secondary case, a fan in said conduit for drawing the air upwardly through the drying chamber 50 and forcing it under pressure into the cleaning chamber, a return conduit leading from the intermediate central portion of the secondary case to the bottom of the main case to return the clean air to the drying chamber, heating means in the bottom of the main case for heating the air as it enters the drying chamber, an air supply conduit leading to the inlet of the fan for replenishing air 55 withdrawn with the heavy matter from the circuit, and an ozonizer disposed in the air supply conduit for supplying ozone to the air entering the secondary case.

In testimony whereof I hereunto affix my signature.
